COMBINED COMPACT AND HOLDER FOR LIPSTICK OR THE LIKE

Frank T. Buchner, Upper Montclair, N.J., assignor to Products Marketing Corporation, Upper Montclair,
N.J., a corporation of Delaware

Filed Feb. 27, 1967, Ser. No. 5,972

Term of patent 14 years

(Cl. D86—10)

FIG. 1

FIG. 3

FIG. 1 is a side elevational view of a combined compact and holder for lipstick or the like, embodying my new design;

FIG. 2 is a left end elevational view thereof;

FIG. 3 is a right end elevational view thereof; and

FIG. 4 is an exploded perspective view thereof showing the compact portion in a partially open condition.

The dominant features of the design reside in the portions shown in full lines; a conventional cosmetic stick being shown in broken lines.

I claim:

The ornamental design for a combined compact and holder for lipstick or the like, as shown and described.
